RAYMOND A. HEISING, OF MILLBURN, NEW JERSEY, ASSIGNOR TO WESTERN ELECTRIC COMPANY, INC., OF NEW YORK, N. Y., A CORPORATION OF NEW YORK.

FREQUENCY ARRANGEMENT IN CARRIER-WAVE SYSTEMS.

Application filed July 20, 1921. Serial No. 486,069.

This invention relates to wave length arrangements, particularly as applied to a system of communication between one or more ship stations and a plurality of shore stations 5 each arranged for multiplex operation.

In multiplex radio transmission, considerations of public convenience, the equitable treatment of competitive interests, etc., impose the necessity of limiting the width of 10 the frequency band assigned to the particular type of service. The problem of multiplex simultaneous transmission with a minimum of interference between the various 15 channels becomes of importance since on its solution depends the maximum traffic that the system can bear.

The problem of multiplex communication between a plurality of fixed stations and a plurality of mobile stations, such as ships, 20 differs in several particulars from that of the more common case of communication between two fixed multiplex stations, whether by high frequency waves over wires or by radio, and is inherently more difficult on account of the greater number of elements involved and the greater diversity of the 25 functions of these elements. The several channels at each shore station must each be kept free from interference with the other channels, as 30 in the ordinary case, and in addition each of the shore stations as a whole must be kept from interference with the other shore stations, so that they can independently communicate with the ship stations without interference therebetween. The space restrictions on shipboard render the problem of 35 selectivity and discrimination against undesired waves difficult and require, in the ordinary case, the use of special receiving 40 apparatus which introduces new difficulties. Because of the mobility of the ship stations, their relation to the several shore stations may continually change with further resultant complication of the problem.

45 The various types of interference which may affect the operation of any particular communication channel may be classified generally as side-tone and as cross talk. The former is measured by the effect of a transmitter wave on the local receiving circuit corresponding to the same two-way conversational unit. Cross talk may be of two kinds, one of which is measured by the effect, in a circuit tuned to a particular frequency, of a 50 current having a different frequency trans-

mitted from a distant station and intended for a different receiving channel. This will be denominated "cross talk in the same direction" or merely "cross talk". Cross talk of a somewhat different order occurs when the 60 transmitted wave corresponding to one conversational unit causes interference in a receiving circuit which is at the same station, but which corresponds to a different conversational unit. This will be denominated 65 for purposes of the present description, "cross talk in opposite directions". These three types of interference phenomena are explained at length in U. S. Patents, 1,548,267 to Heising and 1,548,260 to Espenschied, both 70 granted August 4, 1925.

These various types of interference occur where the circuits at a station are adapted to simultaneously send and receive over any or all of its channels, whether by use of one or a plurality of antennæ. Cross talk can be substantially eliminated by proper spacing between the frequencies associated with the receiving channels at a station, supplemented by frequency selective circuits. The use of 80 this means is shown in a patent to Heising 1,313,483, August 19, 1919. In side-tone and cross talk in opposite directions, the interfering frequency waves originate at the same station where the interference occurs and a balancing means such as that shown in Shreeve Patent 1,378,982, May 24, 1921, may be used to prevent interference, this means being supplemented by frequency selectivity 85 when the transmitting and receiving circuits concerned are arranged to efficiently transmit and receive waves of different frequencies.

If balanced circuits are relied on to prevent side-tone interference and cross talk in opposite directions, the balancing means may well be made much more effective than frequency selective circuits for the purpose of limiting interference, hence a smaller frequency difference may be allowable between 95 oppositely directed channels than between channels in the same direction. In other words, the spacing between the transmission channels at a station (the spacing of the receiving channels, not shown in the figures, being of course the same, in a symmetrical arrangement) is made sufficient to avoid cross talk and the oppositely directed frequencies corresponding to each two-way communication unit are caused to differ by an amount 100 105 110

sufficient to avoid side-tone and cross talk in opposite directions. If the balance is sufficiently accurate, the frequencies transmitted in opposite directions in each conversational unit may be the same, an arrangement most favorable to elimination of cross talk in opposite directions.

However, where the receiving circuit is close to a neighboring transmitting circuit, as compared with the transmitting circuit at a distant station with which it is designed to co-operate, especially if the balancing means is not very effective, the side-tone and cross talk in opposite directions may become very great. In this case resort may be had to particular frequency arrangements in which the frequency spacing between any two oppositely directed carrier waves exceeds the spacing necessary to avoid cross talk in the same direction.

The above explained principles which have heretofore been applied only to systems of multiplex communication between two fixed stations, are applicable with many changes and additions, as will be pointed out in the detailed description, to the more difficult situation in which there are a plurality of multiplex fixed stations which are adapted to communicate with a plurality of mobile stations without communication between the shore stations themselves or between the ship stations themselves.

An object of the invention is to provide various wave length arrangements whereby simultaneous carrier wave communication may be carried on over a plurality of two-way channels without interference.

A more specific object of the present invention, stated comprehensively, is to provide various wave length arrangements whereby one or more shore stations each arranged for multiplex radio operation may, one at a time or simultaneously, communicate over any or all of their channels with one or more ship stations without interference.

The factors which require consideration are primarily the necessary frequency spacing between carrier waves and the physical distances between the stations themselves. According to the present invention, the frequencies of the carrier waves transmitted from a shore station are made to differ from each other and from those transmitted by another shore station or ship station by an amount which permits each carrier wave to be readily separated from any other. The shore stations are preferably spaced at considerable distances apart along the shore and to each are assigned several distinctive transmission frequencies individual to that station. Each ship station is arranged to communicate at any of these transmission frequencies and accordingly may cooperate with each of the shore stations in turn as it progresses along the shore. The transmitting frequencies of a single shore sta-

tion may fall within a range which does not overlap that of any other shore station. This will be termed the "grouped" arrangement. In an alternative arrangement the transmission frequencies of each shore station may be separated by a regular frequency interval which is the same for each station and the series of frequencies appertaining to the other shore stations may then be interspersed between those of one station in such manner as to cause all to fall within a frequency range which they divide into equal frequency intervals. This will be termed the "staggered" arrangement.

The invention will be better understood from the following description taken in connection with the accompanying drawing in which Figs. 1 to 5 inclusive illustrate diagrammatically, various modifications of the system of the invention; Fig. 6 illustrates diagrammatically a form of circuit adapted to be used at a mobile station in the system of the invention and Fig. 7 is a diagrammatic representation of the geographical relations involving the ship and shore stations of the specific system otherwise illustrated by Fig. 1.

Figures 1 to 5 have been arranged so as to refer to a common frequency scale shown at the left of Fig. 1. Although the actual frequency range chosen is merely typical of any desired range, it serves to illustrate the practical aspect of the problem. The different transmitting channel frequencies of the shore stations are denoted by different numerals such as 1 to 12 inclusive and the numerical magnitude of each of these frequencies may be readily ascertained by referring to the frequency scale at the left. The channels corresponding to the different shore stations are distinguished by the use of different underscore lines. It should be clearly understood that the charts of these figures show merely the frequency spacing of various channels and do not indicate the relative positions of the shore stations or their positional relation to the ship stations. The transmitting channel frequencies of the ship stations are denoted by primed numerals, it being understood that for a given two-way communication from ship to shore, the shore outgoing transmission will be identified by the carrier wave frequency of a particular numeral and the ship outgoing transmission (i. e., the shore incoming transmission) will be accomplished by the carrier wave frequency of the same numeral primed. When a ship is most favorably located as to radio operation with respect to a given shore station by being nearest to it, it is assumed that it will communicate with that particular shore station and use the carrier wave frequencies assigned thereto. It is also assumed that any given frequency channel is in use by only one ship station at a time.

Referring to Fig. 1, there is provided an arrangement whereby three shore stations,

each multiplexed for four channels, may simultaneously communicate with ship stations over all channels without interference. The figure shows that the frequencies of the 5 carrier waves transmitted from one shore station are staggered with respect to those transmitted from either of the others. It also shows, by the frequencies corresponding to the same numerals primed, that the frequencies 10 of the outgoing waves from any shore station are staggered with respect to those of the incoming waves at the same shore station, that is, with respect to the frequencies of the cooperating waves transmitted from 15 the ship stations. These two features, with proper spacing, insure the avoidance of interference at the shore stations. Selecting the shore station A, for example, the transmission channels have frequencies 678,000, 714, 20 000, 750,000, and 786,000 cycles. The frequencies of the receiving stations corresponding thereto will, of course, have an equal spacing, and it will be seen by reference to the 25 corresponding ship channels that they employ carrier waves of frequencies 708,000, 744,000, 780,000, and 816,000 cycles.

Usually an arrangement of the type illustrated in Fig. 1 and designed to give just sufficient spacing to prevent cross talk in opposite directions will give more than sufficient spacing to prevent side-tone and much greater spacing than is necessary to prevent cross talk in the same direction. For example, as 30 illustrated in Fig. 1, there is a spacing for prevention of cross talk in opposite directions of 6,000 cycles between a receiving frequency and the closest transmitting frequency at the same station. There is a spacing of 30,000 cycles, which is more than sufficient to prevent side tone, between two 35 oppositely directed channels which together serve for two-way communication. There is a spacing of 36,000 cycles, which is much more than sufficient to prevent cross talk in 40 the same direction, between the carrier frequency of the received wave and the nearest received carrier frequency at the same station.

As regards the effect on the receiving circuits of station A, of two-way transmissions 50 from the remaining shore stations to the ship stations communicating therewith, there is a spacing, for the prevention of interference, of 6,000 cycles between any receiving frequency and the nearest carrier frequency transmitted from another shore station in the system. This type of interference is not strictly in the nature of crosstalk in the same direction, because there is no normal communication between the shore stations. It 55 partakes more of the nature of crosstalk in opposite directions, differing from the conventional form in that the interfering wave comes from a different, noncommunicating, 60 station, instead of from the same station.

Each ship station is intended to communicate with the nearest shore station, and in the practical case the spacing between shore stations is great as compared with the distances over which the radio communication is being 70 carried. This frequency spacing, viz, 6,000 cycles, may therefore be sufficient, even though much greater frequency spacing may be required between channels associated with the same station. There is a corresponding 75 frequency separation of at least 12,000 cycles between such shore station receiving frequencies and the nearest transmitting frequency employed at a ship station designed to communicate with a different shore station. There is therefore enough separation, 80 when aided by the different distances separating a certain ship station from the communicating and non-communicating shore stations, to prevent crosstalk in the same direction due to such transmissions. The frequency considerations apply with equal effect to interference at the ship stations.

A geographical layout in which it is assumed that the frequency allocation is that of the system illustrated by Fig. 1 but the principle of which is equally applicable to Figs. 2 to 5 is disclosed in Fig. 7. It is the particular purpose of this figure to indicate, 90 consistently with the prior description, the fact that a ship moving along the coast illustrated in the figure at all times communicates with its nearest shore station, therefore utilizing in turn a channel, or the channels, allocated to the various shore stations. There is thus made possible, as is elsewhere explained, a compensation for a condition of frequency spacing which under other circumstances would be too small, by the expedient of using 95 a greater geographical spacing between the stations which, under such other circumstances, would tend to interfere, than between the communicating stations. The overall result is a greater concentration of channels in 100 a given total frequency range than would otherwise be possible. In the figure each multiplex shore station is indicated by two blocks representing respectively the transmitting and receiving terminus. The arrows 105 on the broken lines connecting the symbolic ships at the right with these termini indicate the presumed directions of transmission. The labels attached to these lines indicate the corresponding frequencies, consistently 110 with the frequency allocation of Fig. 1.

The foregoing discussion does not presuppose any particular type of radio transmission and reception system. For example, a simple system involving an antenna transmit-receive switch might be employed.

Another system which is now well known makes use of high frequency oscillations at the receiver which are combined with incoming waves of considerably different frequency to produce difference or intermediate fre-

quency waves which are modified in the same manner as the incoming waves.

Fig. 6 illustrates a system adapted to operate according to this method. With the switch 1 closed, ether waves incident on receiving antenna AN_2 are combined with a wave from oscillator O and detected by demodulator D_1 . The resulting difference or intermediate frequency component is selected by a band filter BF and again detected by the device D_2 to yield the desired signal frequency waves which are transmitted over low frequency line 2. For a more detailed disclosure of a system of this type, reference is made to the U. S. patent to Osborne 1,361,487, December 7, 1920. The auxiliary source O may be employed as the primary energy source for the related transmitting circuit at the same station by the use of the additional circuits shown near the top of the figure, by means of which low frequency signals originating in line 2 may be transmitted over line 3 to device M in which the high frequency waves from source O are modulated by the signal waves. The resultant wave may be transmitted, after amplification by amplifier A , by antenna AN_1 . In order that the oscillator O may serve a dual function, as an auxiliary energy source for the receiving circuit and primary energy source for the transmitting circuit, the switch 1 may be closed. In some cases, oscillations generated by source O may be radiated directly to the receiving antenna AN_2 by the transmitting antenna, switch 1 being open. The artificial network N , with associated circuits, is used in well known manner to conjugately connect the transmitting and receiving circuits to the common low frequency line 2. For purposes of identification, the method of operation in which the carrier wave used for transmission is combined with the incoming carrier wave to produce the modified intermediate frequency will be hereinafter denominated "modified intermediate frequency system."

Systems like that shown in Fig. 6, particularly the modified form, are especially adapted to ship working and in the following discussion of the frequency arrangements as affected by these specific types of systems, reference will particularly be had thereto, although it is to be understood that, except for effects introduced on account of the mobility of the ship stations, the conclusions will apply equally to ship or shore working.

As indicating the nature of the interference phenomena introduced by these specific types and the differences therebetween, it is to be noted that in the modified intermediate frequency system, the intermediate frequency is normally derived from the interaction of the transmitted and received frequencies at a station, but may be derived from the interaction of other frequencies associated

with the system as a whole, giving rise to undesirable interference effects. In the intermediate frequency system of the general type disclosed in the Osborne patent, the intermediate frequency is normally under the control of the operator and may be made different from any intermediate frequency derivable from the interaction of any two of the transmitted wave frequencies in the system, although the system is still subject, to some extent, to undesirable interference effects of the kind just described. Except for this qualification, the conditions are essentially similar for the two types. For convenience, the modified intermediate frequency system will be assumed in the following description:

Considering ship station 6', for example, which transmits at 768,000 cycles and receives at 738,000 cycles, an intermediate frequency of 30,000 cycles results. The same intermediate frequency tends to result from reception of the undesired frequency from channel 11 of shore station B. Tuning of the ship station antenna is partly relied on to eliminate this undesired frequency wave, and if the intermediate frequency is sufficiently great will permit response to the desired wave without response to the undesired wave. Moreover, the interfering wave comes from a different land station, and accordingly tuning will be assisted by distance, since a ship station normally communicates with the nearest shore station. Other combinations of frequencies which would give the same intermediate frequencies, such as those associated with channels 7, 7' and 10, 5' are even less favorably related to the channel 6', and can easily be discriminated against. Combinations giving intermediate frequencies different from 30,000 are avoided by intermediate frequency selection.

In the system of Fig. 1, as in the others to be described, a ship station may communicate with another ship station by temporarily assuming a channel of a shore station. If in the system of Fig. 1 one of the three shore stations were to be dispensed with, the carrier frequencies which had been assigned to it could be conveniently used for ship-to-ship communication.

It is obvious that the underlying principles characterizing the operation of the system as described may be employed in other frequency arrangements, and the number of channels and their frequencies may differ greatly from those shown.

Fig. 2 shows a system similar to that of Fig. 1, but adaptable to use with two shore stations. The frequency difference available for prevention of cross talk in opposite directions is the same as in Fig. 1 and on account of the smaller total number of channels used the arrangement permits a smaller frequency in-

terval between transmitting channels at a station, and also a smaller intermediate frequency, which intervals are nevertheless sufficient in the usual case.

Fig. 3 illustrates a case suggested above in which greater separation of frequencies is required for prevention of side tone or cross talk in opposite directions than is offered by the staggered arrangement. Since, even in the staggered arrangement, the frequency difference between oppositely directed channels of a two-way unit may be made as great as desired, and greater than the separation between transmitting channels of a station, the decision to use the grouped arrangement illustrated would, in a practical case, be determined by the conditions affecting cross talk in opposite directions. By the arrangement of Fig. 3, the spacing between frequencies at each station may be as low as that required for this limiting factor, that is there must be sufficient selectivity to avoid cross talk. It is apparent that with an equal number of channels, the economy of frequency space with the present arrangement is comparable with that of the frequency arrangement of Figs. 1 and 2, although the intermediate frequency for duplex operation of the shore stations is greater. It is characteristic of this arrangement, as of the others, that for the purpose of avoiding interference, selectivity of the ship antennae is aided by distance. Moreover, with this arrangement, there are no interfering shore station frequencies which can react with a particular ship frequency to produce the intermediate frequency normally produced at that ship station. Hence the type of interference at a ship station resulting from the use of the modified intermediate frequency system in an arrangement like that of Fig. 1, is not present. As in the cases of the other arrangements considered, the alternative methods of receiving may be used.

Figs. 4 and 5 show arrangements illustrating the opposite extreme, in which the frequencies of oppositely directed channels are the same. The shore station circuits, therefore, require excellent balance in order to prevent side-tone. Except for the conditions affecting side-tone interference, these arrangements are quite similar to those of Figs. 2 and 3. That of Fig. 4 will be used where it is more important to avoid interference between shore stations; that of Fig. 5, when it is more important to avoid either cross talk in the same or opposite directions at a given shore station. The modified intermediate frequency method of receiving at the ship stations, obviously, cannot be used. If the other type of intermediate frequency method is used, the ship antennae may be sharply tuned to the desired frequency. If the latter method is used, in so far as the tuning may unavoidably be broad enough to ad-

mit currents of frequencies producing an interfering intermediate frequency, the problem is essentially similar to that of arrangements 1 and 2, although with a relatively small intermediate frequency, the interfering frequencies may both originate at the same shore station and tuning would not, in this particular case, be aided by distance.

Although the condition has been assumed, in the description, of a plurality of shore station channels with each of which there corresponds a ship station channel, it is to be understood that the system of the invention does not necessarily require as many ship stations as there are channels since a portion only of said channels may be used at one time, and in fact a single ship may in turn occupy each one of the channels. According to the assumed arrangement, involving the use of a plurality of ship stations each individual to a shore station channel, the conditions would be essentially the same if the several stations described as ship stations were fixed stations, either ship or shore, and accordingly the arrangements of the invention are to be understood as applying equally well to such a system. The expression "intermediate frequency system" or the like will frequently be used in the claims in defining a method of receiving, intended to cover both the general and modified forms, above described.

Having described various arrangements of the invention in detail, the features which are considered novel will be covered both broadly and specifically in the appended claims.

What is claimed is:

1. A system of radio communication comprising a group of multi-two-way-channel stations, a second group of two-way-channel stations, a channel of each being adapted to cooperate with a channel of one of the first mentioned stations, the distance between cooperating stations being substantially less than that between any two non-cooperating stations in different groups of stations, and transmitting and receiving circuits at each of said stations, the frequency spacing between the receiving channels of each of the stations of the first group being substantially greater than the minimum spacing between the receiving channels of the different stations of the first group.

2. A system of radio communication comprising a plurality of fixed stations, constituting one group, each provided with a plurality of two-way channels, a plurality of other stations, constituting another group, each having a two-way channel arranged to cooperate with an individual two-way channel of one of the stations of the first group, the distance between stations provided with cooperating channels being substantially less than that between any other two stations in different groups, and the frequency between the receiving channels of each of the stations

- of the first group being greater than the minimum frequency spacing between two oppositely directed channels belonging to different stations of the first group.
5. 3. A system of radio communication comprising a plurality of fixed stations each provided with a plurality of two-way channels, the channels at the several stations being arranged to cooperate with other stations located at points separated from the respective cooperating fixed stations by distances which are substantially less than the distances between such fixed stations, the frequency spacing of the receiving channels at each of said fixed stations being adequate to prevent cross talk in the same direction, the frequency spacing, including zero spacing, of cooperating channels at each of such fixed stations being adequate to prevent side-tone and with relation to the other frequencies, being such that there is adequate separation between the normal receiving frequencies at each of said fixed stations and transmitting frequencies of non-cooperating channels to prevent crosstalk in opposite directions and the receiving frequencies of the various fixed stations being so related to each other as to provide a substantially smaller minimum spacing between receiving frequencies of the different fixed stations, and also a substantially smaller minimum spacing between the receiving frequencies at any one of such fixed stations and the transmitting frequencies of others of

said fixed stations, than between the receiving frequencies at the same fixed station. 35

4. The system of claim 3 in which the spacing of cooperating frequencies is greater than zero.

5. The system of claim 3 including a cooperating station comprising a modified intermediate frequency system at each of a plurality of said points and in which the spacing of the cooperating frequencies, with relation to the remaining frequencies, is such that the interfering frequency nearest to the desired receiving frequency at each of said cooperating stations is transmitted from a non-cooperating fixed station. 40 45

6. The system of claim 3, including at least one mobile cooperating station, each of which is adapted to sequentially occupy positions near a plurality of said points and to cooperate with a channel at that fixed station which is arranged to cooperate with a station at the point where the mobile station is positioned, each of said mobile stations comprising a modified intermediate frequency system, the spacing of the cooperating frequencies, with relation to the remaining frequencies, being such that the interfering frequency nearest to the desired receiving frequency at each of said mobile stations is transmitted from a non-cooperating station. 50 55 60

In witness whereof, I hereunto subscribe my name this 16th day of July, A. D., 1921.

RAYMOND A. HEISING.
